(57) **CLAIM**

The ornamental design for a liquid crystal display (LCD) monitor, as shown and described.

DESCRIPTION

FIG. 1 is a perspective view of a liquid crystal display (LCD) monitor showing our new design;
FIG. 2 is a front view thereof;
FIG. 3 is a rear view thereof;
FIG. 4 is a left side view thereof where the right side view is a mirror image;
FIG. 5 is a top plan view thereof;
FIG. 6 is a bottom plan view thereof; and,
FIG. 7 is a reference perspective view thereof in a condition that the screen of the liquid crystal display (LCD) monitor is swivelled at an angle of 90 degrees.
The broken lines are for illustrative purposes only and form no part of the claimed design.
